FEED GUIDE FOR PLATEN PRESSES

George G. Schierholz, El Cajon, Calif.

Application June 22, 1932, Serial No. 618,743

12 Claims. (Cl. 101—415)

This invention relates to and has for a purpose the provision of a feed guide structurally characterized in a manner to enable it to be rigidly secured to the top or draw sheet of a platen packing against any and all displacements by the action of sheets or cards of any weight dropping against the gaging or stop surface of the guide as the sheets are being fed, to the end of promoting accurate register of the sheets and preventing spoiling of the work as a result of shifting of the guide from its adjusted position, all while preventing any drag upon, or resistance to, the movement of the sheets as they strike and slide across the gaging surface.

It is a further purpose of this invention to provide a feed guide which is readily applied to the draw sheet and is easily adjusted and clamped rigidly in a fixed position on the draw sheet against displacement under the most severe service conditions, all while affording the desirable qualities of structural simplicity, compactness and inexpensiveness of manufacture.

Only one form of the invention will be described, following which the novel features thereof will be pointed out in claims.

In the accompanying drawing,

Figure 1 is a view showing in plan one form of feed guide embodying this invention, secured to a draw sheet;

Figure 2 is a view similar to Figure 1 and illustrating the manner in which the feed guide is to be applied to the draw sheet;

Figure 3 is a vertical sectional view taken on the line 3—3 of Figure 1, with the feed guide in closed position and clamped to the draw sheet;

Figure 4 is a view similar to Figure 3, but showing the feed guide in open position;

Figure 5 is a vertical sectional view taken on the line 5—5 of Figure 1, with the feed guide in closed position and clamped to the draw sheet;

Figure 6 is a view similar to Figure 5 but illustrating a position of the feed guide prior to clamping same to the draw sheet;

Figures 7 and 8 are perspective views, respectively illustrating upper and lower clamping elements embodied in the feed guide.

Referring specifically to the drawing, wherein similar reference characters designate similar parts in each of the several views, this invention in its present embodiment comprises a pair of clamping elements in the form of metal plates 10 and 11 of substantially rectangular outline. The lower plate 10 is bent along one edge to provide a lateral projection 12 which in the use of the guide defines an upright gaging surface 13

which is adapted to be struck by the sheets being fed, so as to limit the movement of and properly position the sheets on the platen.

From the upper edge of the projection 12 extends an arm 14 which overlies the plate 10 in spaced parallel relation thereto and is rigidly connected intermediate its ends to the plate by a rivet 15. The free extremity of the arm terminates at a location substantially central of the plate, and the arm functions as an abutment 60 in a manner to be later described.

The opposite end portions of the plate 10 are provided with flat gripping surfaces 16—16 which may if desired be roughened in any suitable manner. The plate 10 is further provided with spaced 70 openings 17 and 18, (Figure 7), and the material of the plate is downstruck and upstruck at 19 and 20, respectively, to receive and guide a spring tongue 21 which is passed through these openings and also through an opening 22 (Figure 7) in the 75 projection 12 to extend in advance of the gaging surface 13 for the purpose of confining a sheet against upward displacement from the gaging surface upon striking the latter.

The opposite ends of the projection 12 are extended and bent at a right angle thereto so as to provide tabs 23—23 having semi-circular notches 24 loosely receiving trunnions 25—25 on one edge of the upper plate 11 projecting into a recess 26 in the latter which is of sufficient size to freely 80 receive the arm 14 of the plate 10 when the plates are moved to closed position. It will be clear that the tabs 23—23 form bearings and co-act with the trunnions to hingedly connect the plates 10 and 11 while permitting a relative lateral or vertical movement of the plates as a result of the vertical play of the trunnions in the notches 24.

The end portions of the upper plate 11 are provided with flat gripping surfaces 27—27 (Figure 8) which may be roughened in the manner of the 95 gripping surfaces 16—16, and confront the latter when the plates are closed, for co-action in clamping portions of the draw sheet in a manner to be later described. It is to be noted that those portions of the plate 11 forming the gripping surfaces 27 are oppositely inclined slightly from their point of joinder with the plate to the free edges of the latter for flexing to a position parallel with the gripping surfaces 16 when the plates are clamped in closed position, all for the purpose of effecting a uniform distribution of clamping pressure over the areas of the co-acting gripping surfaces, as will be later more fully described.

In order to rigidly clamp the guide to the draw sheet and secure the plates 10 and 11 in closed 110

position, a cam 28 in the form of a metal disk having a segment of its periphery cut away at 29 and a handle 30 projecting radially therefrom is rotatably mounted on the plate 11 by means of 5 a rivet 31. The location of the cam on the plate 11 is such that with the cam occupying the released position shown in broken lines in Figure 1 the cut away portion 29 of the cam will be directly opposite the free end of the arm 14 and will 10 clear the latter so as to enable the upper plate 11 to be swung to open and closed positions with respect to the lower plate. The top surface of the cam is inclined circumferentially from a high level at the points 32-32 (Figure 1) to substantially 15 a feather edge at the center of the cut away portion 29 so as to provide arcuate wedges 33-33, one or the other of which co-acts with the arm 14 in forcing the plates together and securing them in closed position to rigidly secure the guide 20 to the draw sheet.

In the use of the feed guide as above described, the draw sheet 34 on which is indicated a line 35 to which it is desired to feed the sheets is slit in two places at the intended location for the feed 25 guide. These slits are shown at 36-36 in Figures 1 and 2 and at a right angle to the feed line with one end of the slits extending a short distance across the feed line. The slits are spaced apart a distance approximately equal to the spacing 30 apart of the gripping surfaces 16-16 and 27-27, and are of such length that with the plates occupying open position, the lower plate 10 can be inserted obliquely through one slit as shown in Figure 2 and then inserted into the other slit, so 35 that with the guide centered with respect to the slits, the central portion of the plate 10 will overlie the portion of the draw sheet between the slits, whereas the end portions of the plate having the gripping surfaces 16-16 will underlie 40 portions of the draw sheet at the outer sides of the slits:

The feed guide is now adjusted longitudinally of the slit until the gaging surface 13 is in alignment with the feed line 35, following which the 45 upper plate 11 is swung to closed position, where in its gripping surfaces 27-27 will overlie the aforementioned portions of the draw sheet at the outer sides of the slits. The cam 28 is now rotated to co-act with the arm 14 in exerting a clamping 50 force at a substantially central location relative to the plates, to cause the gripping surfaces to co-act in clamping the interposed portions of the draw sheet. It is to be noted that due to the inclination of the outer end portions of the plate 11, 55 as shown in Figure 6, that the outer edges of the gripping surfaces 27-27 will be the first to strike the underlying portion of the draw sheet at the point's indicated at *a-a* in this figure, and that as the clamping force is applied to the plates, the 60 outer end portions of the plate 11 will be caused to flex until the gripping surfaces 27-27 are parallel to the gripping surfaces 16-16, so that all gripping surfaces bear flatwise and with uniform pressure against the interposed portions of the 65 draw sheet. By this construction, the formation of fulcrums at the points *b-b* in Figure 6, with the attendant failure of obtaining maximum clamping action, is avoided, the clamping pressure created at the central location on the plates being 70 distributed uniformly over the areas of the gripping surfaces. The corners of the plates can be curved very slightly towards the sides of the plates having the gripping surfaces, so as to further aid in insuring a perfect clamping action 75 as such slightly curved corners will be caused to

flatten out as the clamping force is applied by the cam.

As the gaging surface 13 extends from the underside of the lower plate 10, and thus in effect 80 extends below the surface of the draw sheet, there is no possibility of a sheet or card as fed to the guide slipping under the lower plate or dragging at the end of the gaging surface. It will thus be manifest that the gaging surface offers no obstruction to accurate feeding; and that in view 85 of the large gripping surfaces and the manner in which they are related to the draw sheet as well as the manner in which clamping pressure is applied to the gripping surfaces, that the guide will be rigidly secured in its adjusted position 90 against displacement in service, all while enabling the guide to be readily re-adjusted and removed as desired.

What is claimed is:

1. In a printing press, a draw sheet having two spaced apart slits substantially in parallelism; a feed guide comprising two clamping elements one of which is inserted through the slits to overlie the portion of the draw sheet between the slits and to underlie portions of the draw sheet 100 at the outer sides of the slits; the other clamping element overlying the last mentioned portions of the draw sheet; means defining a gaging surface on the guide; and means for securing the elements in clamping engagement with the last 105 mentioned portions of the draw sheet so as to fixedly secure the guide to the draw sheet.

2. In a printing press, a draw sheet having two spaced apart slits substantially in parallelism; a feed guide comprising two clamping elements 110 having gripping surfaces; one of the elements being inserted through the slits to overlie the portion of the draw sheet between the slits, with the gripping surfaces of such element underlying portions of the draw sheet at opposite sides of the 115 slits; the other clamping element having its gripping surfaces overlying the last mentioned portions of the draw sheet; means defining a gaging surface on the guide; securing means for exerting a clamping force upon said elements at 120 a substantially central location thereof; and means whereby the clamping force is caused to be distributed uniformly over the areas of the gripping surfaces of the elements so as to fixedly secure the guide to the draw sheet.

3. A feed guide for platen presses comprising a pair of clamping elements each of which is provided with spaced apart gripping surfaces; securing means for exerting a clamping force upon the elements at a single and substantially central location between the gripping surfaces; means by which the clamping force is caused to be distributed uniformly over the areas of the gripping surfaces; and means defining a gaging 130 surface on one of said elements.

4. A feed guide for platen presses comprising a pair of clamping elements each of which is provided with spaced apart gripping surfaces; an abutment on one of the clamping elements; a cam on the other clamping element co-acting 140 with the abutment to exert a clamping force upon the elements at a single and substantially central location between the elements; and means whereby the clamping force is caused to be distributed uniformly over the areas of the gripping surfaces.

5. A feed guide for platen presses comprising two clamping plates having gripping surfaces at opposite end portions thereof; means for movably connecting the plates to occupy an open 150

- position and a closed position wherein the gripping surfaces of one plate confront the gripping surfaces of the other plate; means for clamping the plates in closed position by exerting a force upon the plates at a location intermediate the gripping surfaces thereof; and means for effecting a uniform distribution of clamping pressure over the areas of the gripping surfaces. 5 80
6. A feed guide for platen presses comprising two clamping plates having gripping surfaces at opposite end portions thereof; means for movably connecting the plates to occupy an open position and a closed position wherein the gripping surfaces of one plate confront the gripping surfaces of the other plate; means for clamping the plates in closed position by exerting a force upon the plates at a location intermediate the gripping surfaces thereof; one of the plates having its gripping surfaces inclined for flexing to a position parallel with the gripping surfaces of the other plate to insure uniform distribution of clamping pressure over the areas of the gripping surfaces. 10 85

- 25 100
- 30 105
- 35 110
- 40 115
- 45 120
- 50 125
7. A feed guide for platen presses comprising a lower clamping plate having spaced apart gripping surfaces and a laterally projecting gaging surface along an edge thereof and intermediate the gripping surfaces; an upper clamping plate hingedly connected to the lower clamping plate and having spaced apart gripping surfaces adapted to confront the gripping surfaces of the lower plate; and means by which the plates can be forced toward each other and retained in closed position to clamp portions of a draw sheet between the plates, the upper plate having its gripping surfaces inclined in a manner to be flexed to a position parallel with the gripping surfaces of the lower plate when the plates are clamped together. 130
8. A feed guide for platen presses comprising a lower clamping plate having spaced apart gripping surfaces and a laterally projecting gaging surface along an edge thereof and intermediate the gripping surfaces; and upper clamping plate hingedly connected to the lower clamping plate and having spaced apart gripping surfaces adapted to confront the gripping surfaces of the lower plate; an abutment on the lower plate intermediate its gripping surfaces; and a cam on the upper plate adapted for co-action with the abutment at a substantially central location between the gripping surfaces of the plates in forcing the plates together and retaining them in closed position. 135
9. A feed guide for platen presses comprising a lower clamping plate having spaced apart gripping surfaces and a laterally projecting gaging surface along an edge thereof and intermediate the gripping surfaces; an upper clamping plate hingedly connected to the lower clamping plate and having spaced apart gripping surfaces adapted to confront the gripping surfaces of the lower plate; an arm overlying the lower plate in spaced relation thereto and constituting an abutment; and a cam rotatably mounted on the upper plate for engagement with the abutment to coact therewith in forcing the plates towards each other and retaining them in closed position. 140
10. A feed guide for platen presses comprising a lower clamping plate having spaced apart gripping surfaces and a laterally projecting gaging surface along an edge thereof and intermediate the gripping surfaces; an upper clamping plate hingedly connected to the lower clamping plate and having spaced apart gripping surfaces adapted to confront the gripping surfaces of the lower plate; and means by which the plates can be forced toward each other and retained in closed position to clamp portions of a draw sheet between the plates, the upper plate having its gripping surfaces inclined in a manner to be flexed to a position parallel with the gripping surfaces of the lower plate when the plates are clamped together. 145
11. A feed guide for platen presses comprising two clamping elements one of which is adapted to be inserted through spaced apart slits in a draw sheet to underlie portions of the draw sheet at the outer sides of the slits, and the other of which is adapted to confront said one of the clamping elements and to overlie the draw sheet at said outer portions of the slits; means by which said elements are adapted to be secured in clamping engagement with the portions of the draw sheet at the outer sides of the slits; and means defining a gaging surface on the guide. 150
12. In a printing press, a draw sheet having spaced apart and substantially parallel slits; a clamping member underlying portions of the draw sheet at opposite sides of the slits; a second clamping member overlying said portions of the draw sheet; means for securing said members in clamping engagement with the aforementioned portions of the draw sheet; and means defining a gaging surface on the guide. 155
